(57) **CLAIM**

The ornamental design for an inhaler jar for use with aromatic herbs, spices, and essential oils, as shown and described.

DESCRIPTION

FIG. 1 is a perspective view of an inhaler jar for use with aromatic herbs, spices, and essential oils, showing our new design;

FIG. 2 is an exploded perspective view thereof;

FIG. 3 is an exploded front elevational view thereof;

FIG. 4 is an exploded rear elevational view thereof;

FIG. 5 is an exploded left-side elevational view thereof;

FIG. 6 is an exploded right-side elevational view thereof;

FIG. 7 is an exploded top plan view thereof; and,

FIG. 8 is an exploded bottom plan view thereof.

The broken lines showing a herbs and spices in the jar in the figures depict environmental matter and form no part of the claimed design. The remaining broken lines represent portions of the inhaler jar that form no part of the claimed design.

1 Claim, 8 Drawing Sheets
